CLAIM

The ornamental design for a combined valve assembly and frame head for the transport and handling of gas cylinders, as shown.

DESCRIPTION

FIG. 1 is a front elevation view of a combined valve assembly and frame head for the transport and handling of gas cylinders showing my new design;

FIG. 2 is a rear elevation view thereof;

FIG. 3 is a left side elevation view thereof;

FIG. 4 is a right side elevation view thereof;

FIG. 5 is a top plan view thereof; and

FIG. 6 is a bottom plan view thereof.
